UNITED STATES PATENT OFFICE.

GLENN S. WILLIAMSON, OF NEW YORK, N. Y., ASSIGNOR TO SHURLOC ELEVATOR SAFETY COMPANY, INC., OF NEW YORK, N. Y., A CORPORATION OF NEW YORK.

SAFETY SYSTEM FOR SWINGING ELEVATOR-DOORS.

1,274,127.

Specification of Letters Patent. Patented July 30, 1918.

Application filed December 21, 1917. Serial No. 208,284.

To all whom it may concern:

Be it known that I, GLENN S. WILLIAMSON, a citizen of the United States, residing in the city, county, and State of New York, 5 have invented certain new and useful Improvements in Safety Systems for Swinging Elevator-Doors, of which the following is a specification.

The invention relates to a form of elevator safety system wherein a train of mechanism on the car, operated by the car operator when the car is at a landing and the controller in neutral position, unlocks the landing door lock through the movement of an external shoe or contact piece while simultaneously locking the controller through a suitable device on the car, the car mechanism being retained in actuated condition by means associated with the door lock, so that the controller can not be moved to start the car, while the door is unlocked. A particular purpose of the present invention has been to devise a combination of simple, effective and convenient character, 25 which can be used with swinging doors with the lock below the landing level, this being a type of construction which is more desirable than an overhead installation but hitherto difficult of application to swinging doors. The desired end is now secured by certain novel features of construction, relation and operation, including preferably a specifically novel form of locking and detent mechanism on the shaft face; and the 30 combination with locking mechanism so located of a coöperative member on the swinging door, which normally projects beyond the edge of the door and is withdrawable within the confines thereof preparatory to the opening of the door, such withdrawal of the member being normally prevented by the locking mechanism. The projectable portion of this member is offset, in order to enter the shaft; and, in order to avoid obstruction to persons or freight when the member is withdrawn, its mounting is such as to permit of a compound movement, so that the offset portion can be turned to lie substantially flat against the door.

50 The preferred embodiment of the invention will now be briefly described, reference being had to the accompanying drawings, wherein:

Figure 1 is a fragmentary perspective view showing a portion of the interior of

an elevator car at a landing with an outwardly swinging landing door partly open and the car controller locked in neutral position;

Fig. 2 is a fragmentary perspective view 60 of the door and shaft face with the door closed and locked;

Fig. 3 is a face view of the incased shaft mechanism and a portion of the door member, the condition illustrated being the 65 locked condition;

Fig. 4 is a vertical section on the line 4—4 of Fig. 3;

Fig. 5 is a view similar to Fig. 3 with the cover plate removed, showing the parts in 70 the condition which they assume when the door is open and the car shoe, a portion of which is shown, held by the detent;

Figs. 6 and 7 are front and side elevations of the door member, which in the preferred form illustrated is a vertically-sliding bolt or rod; and 75

Fig. 8 is a cross-section on the line 8—8 of Fig. 6.

1 is a swinging landing door of the single-leaved variety, hinged at one side to swing outwardly away from the shaft. In accordance with the invention the door is provided at its inner side with a raisable member 2, the lower portion 3 of which is offset or doubly right-angled, as shown, in order that it may extend over the sill and downward for a distance in front of the shaft face. The specific form and the mounting of such member may be varied, 80 but in the construction herein preferred it consists of a vertically-sliding rod guided in bearings 4 and 5 at the ends of a slotted plate 7 on the door and provided at its upper end with a laterally-projecting handle 6. 90 A pin 8 projecting from the bolt and traveling in the slot 9 of this plate, keeps the bolt from turning when in its lower or locking position, and guides its lower end in relation to the locking mechanism, presently to be described, when it is being pushed downward. A lateral passage 10 at the upper end of this slot permits the bolt to be turned when in its uppermost position, 95 and also holds it against dropping. In this condition the offset end 3 is raised above the floor level, and folded back close to the door.

The shaft mechanism is mounted in a frame or case 11 having perforated lugs 12 whereby it is attached to the shaft wall. A 110

cover plate 13 leaves one side of the front of this case open to admit the car shoe 14, the top and bottom walls being also recessed for this purpose, as shown at 15. The mechanism comprises instrumentalities for locking the landing door and for retaining the car mechanism, hereinafter described, in actuated condition. The form and arrangement of these instrumentalities may be varied in different cases, but the construction shown is the one here preferred. A door-locking member 16 is pivoted at 17 upon a horizontal axis parallel with the face of the shaft, in the lower part of the case beneath the cover plate, thence extending upward and bearing two reversely-directed lateral arms 18 and 19. Of these the arm 18 is a latch element, having a beveled upper face 20 and a square lower face 21 to coöperate with upwardly-facing locking shoulders 22 on the bolt portion 3. The other arm 19 is a contact element extending into the open part of the case in position to be encountered by the car shoe when the latter is thrust forward.

The top wall of the case has an aperture 23 with a flaring mouth, through which the said bolt portion 3 passes downward into the interior to coöperate with the locking arm 18. In line with the aperture 23 below said arm are bores or barrels 24, 25 for the further guiding of the bolt and to hold a vertically-sliding plunger 26. This plunger is urged upward by an expansion spring 27, and is normally depressed by the bolt, which contacts with its upper end. The side of the plunger is cut away or slabbed off at 28 for the attachment of one arm 29 of a bell-crank member 30, which is pivoted at 31 on a horizontal axis perpendicular to the face of the shaft. This bell-crank member is a detent device, its other arm 32 extending upward from the pivot and bearing a laterally-projecting nose 33, which is constructed and arranged to engage behind the car shoe when the latter is projected so as to press the contact arm 19 toward the back wall of the case. The connection 34 between the bell-crank arm 29 and the plunger is of the pin and slot variety, allowing for the difference in movement of the parts. A spring 35 coiled about the pivot portion of the locking member urges this member away from the back wall and consequently restores it to normal position when the car shoe is retracted.

The car mechanism which terminates in the shoe 14 is preferably of a form made known by another, consisting essentially of a transverse rock-shaft 36 journaled in brackets 37 beneath the car floor and bearing a plurality of crank arms 38, 39 and 40, with the first of which a pedal 41 is connected, extending through the floor of the car with its tread portion convenient to the foot of

the operator, a fore and aft slide bar 42 bearing the shoe being connected with the arm 39, and a vertically-extending controller-locking rod 43 with the arm 40. The upper end of this rod is adapted to enter a notch 44 in an arc segment 45 on the base of the controller lever 46, the arrangement being such that the curved edge of said segment bars movement of the rod, and therefore of the shoe in all positions of the controller except the neutral midposition, at which the rod may enter the notch, thus locking the controller and permitting the projection of the shoe. The car mechanism is self-restoring when the shoe is released by the detent, which may be accomplished by the weight of the rod 43, or by a special counterweight or spring, if desired.

The operation will be briefly summarized. Under the normal condition the door cannot be opened because of the bolt portion 3 projecting downward into the shaft, and this member cannot be raised because it is locked by the engagement of the member 16 with one of its shoulders 22. To open the door the operator must first bring the car to rest approximately at the landing by placing the controller in mid-position. He then steps on the pedal, thus operating the controller lock and projecting the shoe. This presses the locking member 16 backward against the action of its spring, thus releasing the door member or bolt 2, which may be raised. Immediately upon such upward movement of the bolt, the plunger 26 rises under the pressure of its spring, swinging the bell-crank detent 30 about its pivot and causing its nose to enter behind the shoe, which is thus held actuated as long as the said door member is raised and the door is open, and until the door is closed and its member returned to downward-projecting position. The controller lock, being connected with the shoe, is also held throughout the same period, so as to prevent the controller being moved to start the car. When the door member is finally restored to its normal position, the plunger 26 is moved downward, the detent 30 is rocked back to release the car shoe, and the car mechanism then returns to normal condition, freeing the controller, so that the car may then leave the landing. The duplication of the shoulders or notches 22 in the bolt is for additional safety. The manner of raising and lowering and turning the door member has already been described.

What I claim as new and desire to secure by Letters Patent, is:

1. In an elevator safety system, a swinging landing door, a member projectable beyond the edge of the door and withdrawable within the confines thereof, and locking means in the shaft for preventing such withdrawal of the door member, in combination with operator-actuated door-unlocking and

- controller-locking mechanism on the car terminating in a contact shoe coöperative with said locking means in the shaft, and means associated with said locking means 5 for holding the car mechanism in actuated condition.
2. In an elevator safety system, the combination of a swinging landing door, a member movably mounted thereon so as to be projectable downward into the shaft and withdrawable above the floor level, and locking means in the shaft below the door for preventing such withdrawal of the door member, in combination with operator-actuated 10 door-unlocking and controller-locking mechanism on the car terminating in a contact shoe coöperative with said locking means in the shaft, and means associated with said locking means for holding the car mechanism 15 in actuated condition.
3. In an elevator safety system, the combination of a swinging landing door, a member thereon normally projecting beyond the edge of the door and withdrawable within 20 the confines thereof, locking means in the shaft for preventing the withdrawal of said member, operator-actuated door-unlocking and controller-locking mechanism on the car, terminating in a contact shoe for disengaging 25 said locking means from the door member, and means associated with said locking means in the shaft and controlled by the withdrawal and projection of the movable door member before the opening 30 and after the closing of the door, respectively, for retaining the car mechanism in actuated condition when said member is withdrawn and for freeing it when the member 35 is projected.
4. In an elevator safety system, the combination of a swinging landing door, a movable member thereon constructed to project beyond the edge of the door and displaceable from such position to a position within the 40 confines of the door above, mechanism on the face of the shaft comprising locking and detent devices, the former normally engaging and preventing such displacement of the movable member relatively to the door, the 45 detent device being normally pressed out of operative position by said door member and moving automatically when said member is displaced before the opening of the door, and operator-actuated door-unlocking and 50 controller-locking mechanism on the car terminating in a contact shoe adapted to disengage said locking device from the door member and itself to be engaged by said detent device.
5. In an elevator safety system, the combination of a swinging landing door, operator-actuated means on the car including a door-unlocking shoe and means coöordinated therewith for rendering the car controller 55 inoperative, mechanism on the face of the 60
- shaft below the floor level including door-locking and shoe-retaining instrumentalities, and a movable member on the door having an offset angled portion to extend over the sill and downward into the shaft into engagement with the mechanism therein, and a mounting for said member permitting the same to be moved upward and turned sideways to lie substantially flat against the door 65 clear of the landing.
6. In an elevator safety system, the combination of a swinging landing door, operator-actuated means on the car including a contact shoe and therewith coöordinated means for rendering the car controller inoperative, mechanism on the face of the shaft below the floor level coöperative with said shoe and including door-locking and car-mechanism-retaining instrumentalities, and a member mounted on the door for vertical 70 sliding and lateral turning movements and having an offset lower portion to coöperate with the shaft mechanism.
7. In an elevator safety system, the combination of a swinging landing door, operator-actuated means on the car including a door-unlocking shoe and means coöordinated therewith for rendering the car controller inoperative, mechanism on the face of the shaft below the floor level including door-locking and shoe-retaining instrumentalities, and a vertically-sliding and laterally-turning bolt on the landing door having its lower portion offset and provided with an upward-facing locking shoulder to coöperate 75 with the mechanism on the face of the shaft.
8. In an elevator safety system, the combination of a swinging landing door, operator-actuated means on the car including a door-unlocking shoe and means coöordinated therewith for rendering the car controller inoperative, mechanism on the face of the shaft below the floor level including door-locking and shoe-retaining instrumentalities, a vertically-sliding and laterally-turning bolt on the landing door having its lower portion offset and provided with an upward-facing locking shoulder to coöperate with the mechanism on the face of the shaft, and means for preventing turning of said bolt as 80 it is moved downward into engagement with the shaft mechanism.
9. In an elevator safety system, the combination of a swinging landing door, operator-actuated means on the car including a door-unlocking shoe and means coöordinated therewith for rendering the car controller inoperative, mechanism on the face of the shaft below the floor level including door-locking and shoe-retaining instrumentalities, a vertically sliding and laterally-turning bolt on the landing door having its lower portion offset and provided with an upward-facing locking shoulder to coöperate 85 with the mechanism on the face of the shaft.

- shaft, and means for guiding said bolt in relation to the shaft mechanism and for holding the same in its elevated turned position.
- 5 10. In an elevator safety system, the combination of a swinging landing door, a vertically-sliding bolt thereon having an offset angled lower portion provided with an upward-facing locking shoulder; a locking member on the face of the shaft coöperative therewith, a detent device normally depressed by said bolt and tending to move when the bolt is raised, and operator-actuated door-unlocking and controller-locking 10 member on the face of the shaft below the floor level coöperative on the one hand with the car shoe and on the other hand with the door bolt, terminating in a contact shoe adapted to disengage said locking device and to be held by the detent device.
11. In an elevator safety system, the combination with a swinging landing door, a vertically-sliding bolt thereon, its lower portion adapted to project downward into the shaft and provided with an upward-facing locking shoulder, and operator-actuated door-unlocking and controller-locking 15 mechanism on the car, terminating in a contact shoe, of means on the face of the shaft below the floor level coöperative on the one hand with the car shoe and on the other hand with the door bolt, said means comprising a locking member mounted on a horizontal pivot parallel with the face of the shaft and thence extending upward with its upper portion constructed to engage the locking shoulder of the door bolt, a vertical spring-pressed plunger normally depressed by the door bolt, and a pivoted detent member connected with said plunger and adapted to engage and hold the car shoe when the bolt is raised.
12. In an elevator safety system, the combination with a swinging landing door, a vertically-sliding bolt thereon, its lower portion adapted to project downward into the shaft and provided with an upward-facing locking shoulder, and operator-actuated door-unlocking and controller-locking 20 mechanism on the car, terminating in a contact shoe, of means on the face of the shaft below the floor level coöperative on the one hand with the car shoe and on the other hand with the door bolt, said means comprising a locking member mounted on a horizontal pivot parallel with the face of the shaft and thence extending upward with its upper portion constructed to engage the locking shoulder of the door bolt, and a detent normally depressed by the door bolt and adapted to engage the car shoe.
- 25 13. In an elevator safety system, the combination with a swinging landing door, a vertically-sliding bolt thereon, its lower portion adapted to project downward into the shaft and provided with an upward-facing locking shoulder, and operator-actuated door-unlocking and controller-locking mechanism on the car, terminating in a contact shoe, of means on the face of the shaft below the floor level coöperative on the one hand with the car shoe and on the other hand with the door bolt, said means comprising a locking member mounted on a horizontal pivot parallel with the face of the shaft and thence extending upward with its upper portion constructed to engage the locking shoulder of the door bolt, a vertical spring-pressed plunger normally depressed by the door bolt, and a pivoted detent member connected with said plunger and adapted to engage and hold the car shoe when the bolt is raised.
- 30 14. In an elevator safety system, the combination with a swinging landing door, a vertically-sliding bolt thereon, its lower portion adapted to project downward into the shaft and provided with an upward-facing locking shoulder, and operator-actuated door-unlocking and controller-locking mechanism on the car, terminating in a contact shoe, of means on the face of the shaft below the floor level coöperative on the one hand with the car shoe and on the other hand with the door bolt, said means comprising a locking member operable by the car shoe and constructed to engage the locking shoulder on the door bolt, a vertical spring-pressed plunger normally depressed by the door bolt, and a detent connected with said plunger and adapted to engage and hold the car shoe when the bolt is raised.
- 35 15. In testimony whereof, I have signed my name to this specification, in the presence of two subscribing witnesses.
- GLENN S. WILLIAMSON.
